(57) **CLAIM**

The ornamental design for a headset with a microphone, as shown and described.

DESCRIPTION

FIG. 1 is a top front perspective view of a headset with a microphone in an extended position showing our new design;

FIG. 2 is a bottom rear perspective view thereof;

FIG. 3 another top front perspective view thereof;

FIG. 4 is another bottom rear perspective view thereof;

FIG. 5 is a front elevational view thereof;

FIG. 6 is a right side elevational view thereof;

FIG. 7 is a rear elevational view thereof;

FIG. 8 is a left side elevational view thereof;

FIG. 9 is a top plan view thereof;

FIG. 10 is a bottom plan view thereof;

FIG. 11 is a top front perspective view of the headset with the microphone in a retracted position;

FIG. 12 is a bottom rear perspective view thereof;

FIG. 13 another top front perspective view thereof;

FIG. 14 is another bottom rear perspective view thereof;

FIG. 15 is a front elevational view thereof;

FIG. 16 is a right side elevational view thereof;

FIG. 17 is a rear elevational view thereof;

FIG. 18 is a left side elevational view thereof;

FIG. 19 is a top plan view thereof;

FIG. 20 is a bottom plan view thereof;

FIG. 21 is a top front perspective view of the headset with the microphone in a fully extended position;

FIG. 22 is a bottom rear perspective view thereof;

FIG. 23 is a right side elevational view thereof;

FIG. 24 is a left side elevational view thereof;

FIG. 25 is a top plan view thereof; and,

FIG. 26 is a bottom plan view thereof.
